UNITED STATES PATENT OFFICE.

JOHN W. VAIL, OF CHICAGO, ILLINOIS.

DESIGN FOR A BEDSTEAD-FITTING.

45,052.

Specification for Design.

Patented Dec. 16, 1913.

Application filed July 11, 1913. Serial No. 778,594. Term of patent 14 years.

To all whom it may concern:

Be it known that I, JOHN W. VAIL, residing at Chicago, in the county of Cook and State of Illinois, have invented a new, original, and ornamental Design for a Bedstead-Fitting, of which the following is a specification, reference being had to the accompanying drawing, forming part hereof.

The drawing shows, in Figure 1, an outer perspective view of said design; and, in Fig. 2, an inner perspective view of the same.

I claim:

The ornamental design for a bedstead-fitting, as shown and described.

JOHN W. VAIL.

In presence of—

NELLIE B. DEARBORN,
A. C. FISCHER.
